CLAIM

The ornamental design for a set of fatigue relieving wrist and lower arm rests for attachment to a steering wheel, as shown.

DESCRIPTION

FIG. 1 is a front elevated perspective view of a fatigue relieving wrist and lower arm rest for attachment to a left-hand portion of a steering wheel showing my new design;

FIG. 2 is a front elevated perspective view of a fatigue relieving wrist and lower arm rest for attachment to a right-hand portion of a steering wheel showing my design;

FIG. 3 shows a rear elevated left side perspective view of FIG. 1;

FIG. 4 shows a front elevated right side perspective view of FIG. 2;

FIG. 5 shows a rear lower perspective of FIG. 2; and,

FIG. 6 shows a rear lower perspective view of FIG. 1.
